Patented Sept. 19, 1916.

UNITED STATES PATENT OFFICE.

GEORGE FREYTAG, OF SAN FRANCISCO, CALIFORNIA.

BOX-TOE MATERIAL FOR FOOTWEAR.

1,198,905.

Specification of Letters Patent. Patented Sept. 19, 1916.

Application filed May 6, 1916. Serial No. 95,793.

To all whom it may concern:

Be it known that I, GEORGE FREYTAG, a citizen of the United States, residing at San Francisco, in the county of San Francisco, 5 State of California, have invented a new and useful Box-Toe Material for Footwear, of which the following is a specification in such full and clear terms as will enable those skilled in the art to construct and

10 use the same.

This invention relates to a box toe material for footwear, the object of which is to produce a felt, cloth, cloth and paper or cloth and leather box toe, which will retain 15 its shape better than the ordinary leather box toes used for that purpose, and which will not be so easily affected by changes in temperature and moisture as will the leather box toes.

20 Another object of the invention is to produce a substitute for leather which will not absorb water so readily as leather toes.

An embodiment of the invention is shown in the drawing in which the same reference 25 numeral is applied to the same portion throughout, but I am aware that there may be many modifications thereof.

Figures 1 to 4 are plan views of the several parts of the box toe before they are 30 cured together, Fig. 5 is a plan view of a completed toe ready for forming, Figs. 6 to 9 are plan views of slightly differently shaped pieces of material for making a box toe, Fig. 10 is a plan view of the completed 35 toe ready for forming, and Fig. 11 is a vertical sectional view of the toe shown in Fig. 5.

The numeral 1 indicates a more or less semi-circular piece of cloth, 2 a slightly 40 smaller piece of cloth of the same general shape, 3 a semi-circular piece of cloth smaller than the other two and 4 a piece of card board or other heavy material intended to give stiffness to the other portions of the finished box toe.

45 It will be understood that while the term "cloth" is used herein with respect to the several parts of the toe that a suitable felt might be used in place of the cloth, and 50 for stiffening material either felt, cloth, paper or leather could be used.

An insoluble paste consisting of one pound of casein to two ounces of lime is then mixed up and the several parts of the 55 toe are impregnated successively with said

paste. At first the large cloth 1 is impregnated with the paste; after that the small cloth 3 is impregnated with the paste and secured to the first one. Following this the stiffening material 4 is covered with the 60 paste and secured to the member 3, after which the large member 2 is then pasted on the other parts.

It will be observed that none of the four parts going to make up the box toe are exactly the same size, the object being to cause the toe form to taper out at the edges as thin as possible and to make as smooth a finished product as possible. Where very small shoes are made it may be feasible to dispense with the stiffening material 4 and only use a cloth suitably reinforced with smaller pieces and impregnated with the 65 paste.

In Figs. 6, 7, 8 and 9 there is shown a 70 slightly differently shaped series of cloths used for completing the toe. In these figures the numeral 6 indicates the larger cloth, 7 a slightly smaller one, 8 a much smaller 75 cloth and 9 a piece of card board used for 80 a stiffening material and having ends 10 and 11 which project substantially the entire width of the larger pieces of cloth.

It will be understood that while only two shapes have been shown that the particular 85 shape of the felt pattern is a matter that is dependent entirely upon the desired shape of the finished box toe and is not material to the scope of the invention.

After the several layers of fabric, felt, 90 leather or paper are secured together with the casein paste they are dried and are ready to be formed up into the desired shape for the finished footwear. While the casein is 95 not soluble in water the flat box toe material may be softened by placing it in hot or cold water and allowing it to soak for a considerable time, after which the material is formed up and stretched into the desired shape and when again dried will retain that 100 shape indefinitely.

Having thus described my invention what I claim as new and desire to secure by Letters Patent of the United States, is as follows, express reservation being made of permissible modifications:

1. A box toe material for footwear consisting of layers of fabric impregnated with a solution of casein and lime.
2. A box toe material for footwear con- 110

sisting of several layers of cloth impregnated with casein and lime.

3. A box toe material consisting of several layers of cloth, a layer of stiffening between the cloth layers, the series of layers being impregnated with a solution of casein and lime.

4. A box toe material consisting of a plurality of layers of cloth with a layer 10 of stiffening material between the cloth

layers, the entire series being impregnated with a paste of casein and lime.

5. A box toe material consisting of a plurality of layers of cloth, a thickness of paper between the layers of cloth, and a solution 15 of casein and lime impregnating the several layers of cloth and paper.

In testimony whereof I have hereunto set my hand this 29th day of April A. D. 1916.

GEORGE FREYTAG.
